UNITED STATES PATENT OFFICE.

C. NEWTON HAMMOND, OF CANTON, ASSIGNOR OF TWO-THIRDS TO ISAAC N. BEARDSLEE, OF EAST CANTON, PENNSYLVANIA.

ADJUSTABLE BUSINESS-SIGN AND INDICATOR.

SPECIFICATION forming part of Letters Patent No. 389,074, dated September 4, 1888.

Application filed February 13, 1888. Serial No. 263,929. (No model.)

To all whom it may concern:

Be it known that I, C. NEWTON HAMMOND, a citizen of the United States, residing at Canton, in the county of Bradford and State of Pennsylvania, have invented certain new and useful Improvements in Adjustable Illuminated and Transparent Business-Signs; and I do hereby declare the following to be a full, clear, and exact description of the invention, so such as will enable others skilled in the art to which it appertains to make and use the same.

This invention relates to indicators and business-signs.

The object is to provide an indicator for office use which will give information as to the whereabouts of the person sought, and, if absent, the hour of his return, and which indicator shall be comparatively simple and inexpensive of construction and efficient in operation.

The invention consists in an indicator having a flap hinged upon it, means whereby said flap may, when turned, be held to exhibit either side, and stops or cushions against which 25 the flap may bear.

Furthermore, the invention consists in an indicator provided with a flap adapted to be turned to exhibit either side and a spring designed to hold the flap in position.

Furthermore, the invention consists in an indicator having openings in its outer casing, a flap hinged thereon, a spring adapted to hold the flap in position, a band or bands within the casing, and means whereby said band or bands are caused to pass in front of the openings.

Furthermore, the invention consists in an indicator having openings in its outer casing, rollers journaled in the casing, means whereby 40 said rollers may be rotated, a band or bands caused by rotation of the rollers to move past the openings, and stops engaging the rollers.

Furthermore, the invention consists in an indicator having openings in its outer casing, rollers journaled within the casing, a band or bands operated by the rollers, and a spring-actuated pin or stop engaging openings in the rollers.

Furthermore, the invention consists in rollers, each having openings in its circumference, a lever carrying at one end a pin adapted to

engage the openings, and at its other end a key for depressing the lever and operating the pin, and a spring bearing upon the lever to depress the pin; and, finally, in various novel details 55 of construction, hereinafter set forth.

In the accompanying drawings, in which like letters of reference indicate corresponding parts, Figure 1 represents a front elevation of an indicator, showing the flap turned down to uncover the openings. Fig. 2 represents a side elevation of the same. Fig. 3 represents a detail view of the upper rollers and spring stop. Fig. 4 represents a front elevation of the indicator, the flap being turned up to cover the 65 openings; and Fig. 5 represents a vertical section of the same.

A designates a box or casing, suitably constructed, upon the outer face of which, about its center, is hinged a flap, B. The face of the 70 box or casing A may bear the name and occupation of a person, while one side of the flap may bear the words "In Office," as shown in the drawings.

Openings a a' are formed in the face of the 75 box A, above one of which may be the word "At," while above the other may be "Return," or other suitable word or expression. Through each of these openings is displayed a band or ribbon, C C', carried by rollers c c', 80 situated, respectively, near the top and bottom of the interior of the box and journaled therein. The outer journal of each of these rollers extends through the side of the box, and is there provided with a thumb-nut, c², by 85 means of which the rollers are rotated. In the device here illustrated there are shown four rollers arranged in pairs vertically parallel, the upper and lower roller of each pair having attached to it one end of the band or ribbon. Upon one of these bands or ribbons may 90 be printed, painted, or otherwise marked expressions "Drug Store," "About Town," "Out of Town," "Church," "Justice's Office," "Clerk's Office," "Dinner," "Post-Office," 95 "Barber-Shop," or anything of the like, indicating the whereabouts of the person by whom the device is employed, these being displayed through the opening a, above which the word "At" is shown. Any of these expressions may 100 be shown by rotating one of the rollers by means of its thumb-nut.

The outer band is intended to indicate the hour or time of return, being displayed through the opening a' , above which the word "Return" is shown, and upon this band are marked 5 the hours of the day, the days of the week, or such expressions as "Soon," "Wait," &c. It is similarly operated.

When in office, the flap is turned up into position to cover the openings a' , displaying 10 upon its side, now exposed, the expression "In Office."

The position of the flap is insured by springs b' , attached at one end to pins b^2 upon the outer edge of the flap, at a slight distance 15 from its pivot, its opposite end being secured upon the side of the box in a line with the pivot or hinge. Thus it will be seen that whether the flap be in one position or the other the spring will draw it closely against 20 the face of the box and prevent its accidental displacement.

Conveniently situated upon the face of the box are rubber disks a^3 , which act as cushions for the flap when turned into position, and 25 also raise it slightly above the surface of the box to permit it easily to be raised.

To prevent the rollers from being partially rotated through jar or otherwise, and thus from disturbing the adjustment of the bands, 30 a catch, D, is provided above each of the upper rollers, which consists in a pin, d , adapted to engage small openings d' in the inner edges of each of these rollers, the pin being carried by one end of a lever, d^2 , pivoted at its center, the opposite end of the lever being engaged by a key, d^3 , extending upward through the top of the box. The inner ends of the levers are pressed downward by a spring, d^4 , the proper direction in movement of the pins 35 being insured through a guide, d^5 . By depressing the keys d^3 the pins d will rise out of the openings d' and permit of the rollers being rotated by means of the thumb-nuts, which project out of the casing A, and the 40 bands caused to pass the openings a' until the desired expression is shown therethrough, when the pins are allowed again to engage one of the openings, and the rollers are thus firmly held against movement.

45 The bands may be made of some transparent material and a light be placed behind them, which will clearly display the indications thereon. The flap may also be made of transparent material for similar purposes.

50 e represent endless cords or bands, which pass over the upper and lower rollers near their ends, and which serve the purpose of causing the rollers to move simultaneously, and also of imposing sufficient friction upon

the rollers to hold them in any position to 60 which they may be turned.

Having thus fully described my invention, what I claim as new, and desire to secure by Letters Patent, is—

1. In an office-indicator, the combination of 65 a frame or casing provided with one or more openings in its face, whereby the interior may be observed, a hinged flap adapted to cover or uncover said opening or openings, and one or more springs for the purpose of retaining 70 the flap in an open or closed position in relation to the openings, substantially as described.

2. In an indicator, the combination of a frame or case provided with one or more openings in its face, whereby the interior may be 75 observed, a flap adapted to cover or uncover said openings, and springs for the purpose of retaining the flap in an open or closed position, and one or more movable bands located behind 80 said openings, substantially as described. 85

3. In an indicator, the combination of a frame or casing provided with one or more openings in its face, a hinged flap adapted to cover or uncover said openings, springs for the purpose of retaining the flap in either position, and one or more movable bands located 95 behind said openings and attached at both ends to the rollers, the said rollers being provided with handles—such as thumb-nuts—for the purpose of actuating them, substantially as 90 described.

4. In an indicator, the combination of a frame or casing provided with one or more openings, a hinged flap adapted to cover or uncover said openings, a spring or springs for 95 the purpose of retaining the flap in either position, one or more bands located behind said openings, rollers having the ends of said bands attached to them, and spring-stops whereby the rollers will be prevented from accidentally 100 rotating, substantially as described.

5. In an indicator, the combination of a frame or casing, a hinged flap on the face of the casing, one or more springs retaining the flap in an open or closed position, a roller having stop openings in its circumference, a stop adapted to engage said openings, a second roller and a band attached to the rollers adapted to be actuated thereby, and a belt for the purpose of keeping the said band taut, 105 substantially as described.

In testimony whereof I affix my signature in presence of two witnesses.

C. NEWTON HAMMOND.
